SHEET CONTROLLING APPARATUS

Edward F. Dudley, Oak Park, Ill., assignor to
The Miehle Printing Press & Manufacturing
Company, Chicago, Ill., a corporation of Illinois

Application December 16, 1940, Serial No. 370,302

10 Claims.

(Cl. 271—58)

This invention relates to sheet controlling apparatus intended for use on printing presses which are organized to handle sheets in progressive order.

More specifically stated, the invention is particularly adapted for embodiment in that class of printing presses which are known in the trade as the vertical type and which include an impression cylinder mounted for vertical reciprocation, and a sheet transfer table arranged to follow the linear movement of the impression cylinder.

In the operation of such presses, the sheets to be printed are separated from a feeder pile, then fed to and deposited on the transfer table for registration prior to being engaged by the grippers of the impression cylinder. During the down-stroke of the table, a forward tilting motion is imparted to it in order to cause the sheet to slide forwardly until its leading edge is in contact with the front registering guides which may be provided on the impression cylinder or arranged in any other conventional manner. In the particular type of press in connection with which I have chosen to illustrate my invention, the impression cylinder is provided with radial grippers and the stems of two or more of such grippers constitute the front registering guides.

Broadly, the side guide mechanism which I prefer to use includes a rock shaft mounted on the cylinder carriage and extending across the entire width of a transfer table. To this shaft is adjustably secured a side registering arm provided with a side guide and the arm is rocked into and out of its sheet registering position by suitable cam means whereby the rock shaft is actuated. In addition to the rocking movement, the rock shaft, and therewith the side guide, is given a lateral movement for the purpose of side registering the sheets.

It is in connection with registering mechanism such as are described for instance my earlier Patent No. 1,503,492 and in the Patent to B. D. Stevens, No. 1,503,520, that I propose to embody the present invention.

I have found that registering devices of the type disclosed in said patents function quite satisfactorily within certain speed limits of the printing machine and provided, of course, that the stock to be fed is in satisfactory condition. However, at higher speeds it becomes evident that a more positive control of the sheets, while undergoing registration, is required in order to assure good commercial register. Heretofore, the sheets, while on the transfer table, were free so that by

the mere tilting movement of the table they would slide forward and into engagement with the front guides by their own gravity.

When handling light weight stock, such as "onion skin," or stock that would "curl," then quite frequently such tilting of the transfer table would not advance the sheets enough for their leading edge to reach the front guides, resulting in faulty register or in many interruptions which would very considerably reduce the output of the press.

I have, therefore, conceived the idea of providing registering brushes or other flexible members which are carried by the side registering mechanism so as to move therewith and into engagement with the top face of a sheet to be registered. In this manner, as will be apparent from the following description and accompanying drawings, the sheet, during its final forward registering movement, is urged forwardly against the front guides by means of said brushes and the sheet is also held down onto the transfer table, thereby avoiding displacement of the registered sheet.

In addition to these brushes which, of course, are adjustable with relation to the top of the transfer table, I preferably introduce additional means whereby, during the downward, i. e. registering, movement of the side guide mechanism, the front edge of a sheet to be registered shall be straightened out and held down flat, thereby preventing any upward curling of the sheet along the leading, i. e. registering edge.

One of the primary objects of the invention resides in the provision of ingenious means whereby sheets, while being registered, are positively controlled to assure proper registration.

Another object of the invention is the provision of improved means whereby buckling or curling along the leading edge of a sheet to be registered shall be prevented.

A further object of my invention is to provide simple means whereby the use of "back stops" and other similar make-shift devices for bringing the sheets against the front guides shall be eliminated.

These and other objects will become apparent from the following description and accompanying drawings, in which:

Figure 1 is a fractional view of the side guide mechanism and associated parts in connection with which I have applied my invention.

Figure 2 shows the same parts in different positions, namely raised above the sheet transfer table; and

Figures 3 and 4 illustrate conventional means

whereby the side guide mechanism is swung into and out of its operative position, as well as moved laterally for the purpose of side registering the sheets.

Referring to Figure 1, the sheet S is shown in its registered position on the transfer table 10 so that its leading edge 11 abuts against the front registering guide faces 12 provided on two or more of the radial grippers 13 carried by the impression cylinder 14, and the side guide 15 moves against a lateral edge of the sheet. The rock shaft 16, which, as shown in my earlier patent identified above, extends across the entire width of the transfer table 10, has mounted thereon one or more rods 17 which are held in position by any suitable means, such as clamps 18. To the free ends of the rod or rods 17 is secured a cross-bar 19 which also preferably extends over the entire width of the table 10 as shown in said patent to Stevens. This bar carries the registering guide 15 in a manner that the guide may be adjusted and maintained in different positions longitudinally thereon. A groove 20 is formed in the transfer table 10 to accommodate the side guide 15.

The bar 19 also has provided thereon one or more brackets 21 each one of which, by means of a clamp 22 and thumb screw 23, may be moved into different positions over said rod for the purpose of applying the brush 24 carried thereby at the desired points on the top surface of a sheet to be registered. The threaded stem 25 is mounted to slide within bores provided in the bracket and the brush is adjustably arranged so that, by means of the knurled nuts 26 and 27 which are threaded onto the stem, the brush can be moved with relation to a sheet on the table 10. The stem 25 is held against rotation within the bores in the bracket 21; therefore, a micrometer adjustment of the brush 24 is made possible by loosening the nut 26 and by then turning the nut 27.

In order to avoid curling up of a sheet along its leading edge and also to straighten out the leading edge of a sheet before it is presented to the front guides 13, I provide a bar 30 which extends crosswise of the table 10 so that it will cover the entire width of a sheet to be registered. This bar is adjustably secured to the rock shaft 16 by means of arms 31 and clamping brackets 32. In its operative position, as shown in Figure 1, a gap 33 is left between the bar 30 and the top of a sheet to be registered in order to prevent damage to a sheet.

In Figure 2, I have illustrated the side guide mechanism with its associated parts in the inoperative position, namely at the time when a sheet is being fed onto the transfer table 10 by the feeding mechanism of the press.

In the operation of my novel sheet controlling means, namely during the down-stroke of the registering guide 15 when the latter approaches its position shown in Figure 1, the brush 24 lightly engages the sheet on the transfer table 10 so that, during the final down-stroke, the brush urges the sheet forwardly against the front registering faces 12 on the impression cylinder grippers 13 and holds the sheet against displacement on said table.

The bar 30, during its downward movement, causes the front portion of a sheet to straighten out and also prevents any curling up or buckling of the front edge of a sheet while the sheet is being registered.

The conventional means, illustrated in Figure 3 and which preferably may be arranged on one of the vertical side frames of the press, includes

a closed cam, or roller track 35, a roller lever 36 which is rigidly mounted at one end of the rock shaft 16, and a roller 37 which is carried by the free end of said lever and rides within the track 35. The position of the roller 37 shown in full lines in Figure 3 corresponds with that of the parts assumed in Figure 2.

It will be understood that the roller track 35 is stationary and that upon downward movement 10 of the shaft 16 the roller 37 has assumed its position depicted in broken lines in Figure 3 and consequently has swung down the lever 36 and therewith rocked the shaft 16 and its associated parts into their operative position illustrated in Figure 1. During the upward movement of the shaft 16 said parts are again being returned into their inoperative positions as shown in Figure 2.

In Figure 4 I have also shown a conventional means whereby the side register 15 is caused to move laterally for the purpose of side registering the sheets.

This means broadly comprises a roller track or cam 40, which preferably is secured to the side frame 41 of the press. The outer end 42 of the 25 rock shaft 16 carries a bracket 43 on which is arranged a cam roller 44 to rotate freely and to extend within the track of the cam 40. Preferably the rock shaft 16 is guided in a bearing 45, which may be secured to the reciprocating cylinder carriage 46 by means of bolts 47, or the like.

It will be understood that when the cylinder carriage 46 and its associated parts move downwardly from their position depicted in full lines in Figure 4 the roller rides within the cam track 35 40 and is displaced laterally, that is to say to the left, as viewed in Figure 4, together with the rock shaft 16 and the side guide 15 for the purpose of side registering a sheet, and said parts will assume the position shown in broken lines in Figure 4. 40 When the cylinder carriage 46 is moved upward during the printing stroke of the press, then the roller 44 and therewith the side guide mechanism are restored into their inoperative positions shown in full lines in Figure 4.

I wish it to be understood that, while I have illustrated and described a preferred form and embodiment of my invention, certain modifications could be introduced without departing from the principle of my invention; therefore, I intend to cover any such modifications which come within the meaning of the appended claims.

I claim:

1. In a printing press of the class specified, and including an impression cylinder mounted for reciprocation in a linear path, the combination of front registering guides on said cylinder, a sheet support, and sheet controlling means operative to swing into the plane of a sheet placed onto said support and including at least one flexible element adapted to engage the top surface of such sheet, to thereby urge its leading edge into contact with said guides and hold it in registered position on said support.

2. In a printing press of the class specified, and including an impression cylinder mounted for reciprocation in a linear path, the combination of front registering guides on said cylinder, a sheet support, sheet controlling means operative to swing into the plane of a sheet placed onto said support and including at least one flexible element adapted to engage the top surface of such sheet, to thereby urge its leading edge into contact with said guides and hold it in registered position on said support, and additional means effective during the movement of said controlling

means into the plane of a sheet, and while at rest, to straighten out and hold down the leading edge of a sheet to be registered.

3. In a printing press of the class specified, and including an impression cylinder mounted for reciprocation in a linear path, the combination of front registering guides on said cylinder, a sheet support, movable side registering means cooperatively associated with said support, and sheet controlling means movable with the latter and operative to swing into the plane of a sheet placed onto the support and including at least one flexible element adapted to engage the top surface of such sheet, to thereby urge its leading edge into contact with said guides and hold it in registered position on said support.

4. In a printing press of the class specified, and including an impression cylinder mounted for reciprocation in a linear path, the combination of front registering guides on said cylinder, a sheet support, movable side registering means cooperatively associated with said support, sheet controlling means movable with the latter and operative to swing into the plane of a sheet placed onto said support and including at least one flexible element adapted to engage the top surface of such sheet, to thereby urge its leading edge into contact with said guides and hold it in registered position on said support, and additional means effective during the movement of said controlling means into the plane of a sheet, and while at rest, to straighten out and hold down the leading edge of a sheet to be registered.

5. In a printing press of the class specified, and including a rotary impression cylinder mounted for reciprocation in a linear path, the combination of front registering guides on said cylinder, a sheet support arranged to reciprocate with said cylinder, and sheet controlling means operative to swing into the plane of a sheet placed onto said support during the reciprocatory movement of said cylinder and table, and including at least one flexible element adapted to engage the top surface of such sheet, to thereby urge its leading edge into contact with said guides and hold it in registered position on said support.

6. In combination with a sheet registering device arranged to be swung from an inoperative, raised position into the plane of a sheet supporting member for registering a sheet thereon, the provision of sheet controlling means including, at least one flexible element arranged to move with said device and into engagement with the top surface of a sheet to be registered, to thereby urge the leading edge of said sheet into contact with the front registering guides and hold it in registered position on said member.

7. In combination with a sheet registering device arranged to be swung from an inoperative, raised position into the plane of a sheet supporting member for registering a sheet thereon, the provision of sheet controlling means including, at least one flexible element arranged to move with said registering device and into engagement with the top surface of a sheet to be registered, to thereby urge the leading edge of said sheet into

contact with the front registering guides and hold it in registered position on said member, and additional means effective during the movement of said controlling means into engagement with the top surface of a sheet to be registered, and while at rest, to straighten out and hold down the leading edge of a sheet to be registered.

8. In combination with a sheet registering device arranged to be swung from an inoperative, raised position into the plane of a sheet supporting member for registering a sheet thereon, the provision of sheet controlling means including at least one flexible element carried by said registering device and arranged to move with the latter and into engagement with the top surface of a sheet to be registered, to thereby urge the leading edge of said sheet into contact with front registering guides and hold it in registered position on said member, and additional means also moving with said device and effective during the movement of said device into the plane of a sheet on said supporting member, and while at rest, to straighten out and hold down the leading edge of a sheet to be registered.

9. In combination with a sheet registering device arranged to be swung from an inoperative, raised position into the plane of a sheet supporting member for registering a sheet thereon, the provision of sheet controlling means including, at least one flexible element arranged to move with said registering device and into engagement with the top surface of a sheet to be registered, to thereby urge the leading edge of said sheet into contact with the front registering guides and hold it in registered position on said member, a micrometer device for adjustment of said flexible element or elements with relation to a sheet on said supporting member, and additional, adjustable means effective during the movement of said controlling means into engagement with the top surface of a sheet to be registered, and while at rest, to straighten out and hold down the leading edge of a sheet to be registered.

10. In combination with a sheet registering device arranged to be swung from an inoperative, raised position into the plane of a sheet supporting member for registering a sheet thereon, the provision of sheet controlling means including, at least one flexible element carried by said registering device and arranged to move with the latter and into engagement with the top surface of a sheet to be registered, to thereby urge the leading edge of said sheet into contact with the front registering guides and hold it in registered position on said supporting member, a micrometer device for adjustment of said flexible element or elements with relation to a sheet on said supporting member, and additional, adjustable means also moving with said device and effective during the movement of said controlling means into engagement with the top surface of a sheet to be registered, and while at rest, to straighten out and hold down the leading edge of a sheet to be registered.

EDWARD F. DUDLEY.
